UNITED STATES PATENT OFFICE.

JOHN F. O'ROURKE, OF NEW YORK, N. Y.

TUNNELING.

1,277,107.

Specification of Letters Patent. Patented Aug. 27, 1918.

Application filed February 1, 1918. Serial No. 214,877.

To all whom it may concern:

Be it known that I, JOHN F. O'ROURKE, a citizen of the United States, and resident of New York city, borough of Manhattan, 5 in the county of New York and State of New York, have invented certain new and useful Improvements in Tunneling, of which the following is a specification.

Shields have heretofore been used in the 10 construction of tunnel's in which the excavation was carried forward at the front of the shield for distances corresponding to the length of the tunnel ring. The excavation usually ended in a vertical face held in place 15 with breast boards when the material at the face would not stand up of itself and into such space the shield was shoved forward thus providing space in the tail of the shield in which to erect another ring. Repeating 20 this process of excavation, shoving and erecting successive rings constitutes the method of shield tunneling.

As the bottom of the shield is usually 25 built about the length of a ring or shove shorter than the top, the face of the excavation lies just under the end of the shield at the top, and a slope of earth is allowed to stand at the bottom when the ground permits, into which the shield readily shoves, 30 so that generally the vertical face of the excavation extends only part way to the bottom. In soft ground, like silt, the shield is closed in front and shoves the ground ahead of it, or the shield may have a small opening 35 through which some of the ground enters during a shove, but this condition is unimportant in designing the shield as it must be prepared to go through harder ground when encountered, and so is always built 40 with an open face overhanging at the top. It is also usual to divide the shield into two or three levels at the forward end divided by platforms fitted with extensible fronts 45 operated with hydraulic jacks from which the excavation is carried on, and which hold the timbering and breast boards before and during the shove. These platforms have always been designed to reach the one vertical face heretofore used and the form of the 50 shield itself has been adapted to inclose only one vertical face of the excavation.

When a tunnel is under water or in water-bearing ground compressed air is generally used. The pressure is usually maintained 55 in the tunnel and shield alike, equal to the pressure in the ground water at or near the

bottom of the shield, so that the pressure of the compressed air at the top of the shield is in excess of the pressure of the ground water at that level, proportional to the 60 height of the shield. The tendency of this unbalanced pressure is to blow out the ground at the top of the shield, which sometimes happens when the cover of earth is insufficient to hold the air. The usual practice to prevent this is to maintain a cover of earth one and a quarter times the diameter of the tunnel above the shield, which gives a small margin of weight in excess of 65 the lifting power of the unbalanced air 70 pressure.

It is obvious that if the air pressure at the top of the shield could be kept at something near the water pressure at that point that the danger of "blowouts" would be greatly 75 lessened, and that the work would be done in the upper part of the shield under less air pressure and with less cost for power and labor. This fact was perceived in some of the larger tunnels that have been constructed, and in the shields for which air chambers on separate levels were provided, but it was found impossible, in the design of shields used, to prevent the higher pressure in the lower air chamber from passing into 80 that above at the common vertical face. As the tunnels in which the attempt was made, so far as I am aware, were of moderate diameter and well within the limits up to which clay blankets could be used of 85 sufficient thickness to counter-balance the unbalanced air pressure, the work was done without the use of the multiple air pressures. Had a tunnel been designed of such size that the clay blankets would block up 90 the river above, such tunnels would not have been built by the known methods and a number of smaller tunnels would have been built, 95 therefore small tunnels have been the rule heretofore.

One object of my invention is to provide 100 means by which air chambers in the forward part of the shield on successive levels can maintain air pressures in each suitable for working against the water pressure in 105 the ground in front of itself without being affected by the higher air pressure of a lower level. This is accomplished by having the faces of different levels in the shield in different planes, stepping forward from one another from the top chamber to the bottom. This locates the faces of the excava- 110

tion in corresponding steps, separated from each other by floors in the shield, and their cutting edges on the forward parts thereof, which are air tight and compel the compressed air that escapes into the ground to ascend without obtaining access to the chamber above. Entrance of air from a chamber below into a chamber above is effectually prevented by the fact that the compressed air when it enters the ground and commences to rise, immediately expands to the pressure of the adjacent ground water, which pressure is constantly lessening upward, so that the escaping air in the ground can never be at a higher pressure than that of the air in the chamber it is passing, since that pressure also is regulated by the water pressure in front.

There might be circumstances in which it would be advantageous to have the air chambers step backward from top to bottom and also cases in which the air chambers would be given independent telescopic motion in the shield, but the principle remains the same of maintaining the faces of the excavation in different vertical planes so as to spill separately the compressed air of different pressures out into the ground where they can harmlessly expand unconfined.

The height of the floors above one another can be made as most convenient for the excavation and unbalanced air pressure. The unbalanced air pressure at the top of the shield in the case of multiple air chambers is only that of the top chamber, so that the necessary earth cover, or clay blanket in lieu of same, is no longer required proportional to the diameter of the shield but to the height of the top air chamber where that height is not less than that of the chamber or chambers below, and so with my improved shield the former limitation of size of tunnels to be constructed with the use of compressed air disappears.

Another very important object accomplished by having air chambers capable of maintaining different pressures at different levels is that the pressure in the tunnel itself can be maintained at a desired pressure independent of the air pressures in the air chambers. The doors of the air locks are hung on the sides of the openings against which the pressure comes. The air locks are fitted with butts inside and outside of the openings so that when the doors are hung correspondingly they act equally well whether the higher pressure is in the air chamber or in the tunnel. The aforesaid independence of pressures between those at the front of the shield and that in the tunnel proper gives great latitude in the use of compressed air in tunnel construction. Heretofore if the top of the shield was above water level in loose ground with enough water in the ground at the bottom part of the shield to require the use of compressed air, great difficulty was encountered because of the water, even in small diameter tunnels. By the use of my improved shield, having air chambers adapted for different pressures corresponding to the water pressures at their fronts, the aforesaid difficulties are overcome. Air chambers above the water level would contain free air. Such free air chambers and any chambers below water level holding compressed air of less pressure than that in the tunnel, would have their air locks arranged to hold against the tunnel pressure and thus former difficulties in holding compressed air in a tunnel that is partly above water level is obviated. The importance of the foregoing is obvious when it is considered that improved methods of shield tunneling enable such tunnels to be driven under city streets without disturbing the surface or adjoining buildings and that by reason of this improved shield the matter of where the top of the ground water lies is no longer of importance, since compressed air can be used with the top of the water lying at any level in the shield.

My invention also comprises novel details of improvement and combinations of parts that will be more fully hereinafter set forth and then pointed out in the claims.

Reference is to be had to the accompanying drawings forming part hereof, wherein, Figure 1 is a vertical section of a tunnel shield embodying my invention, illustrating the location of the sheeting or breast boarding at the face of several compartments before shoving the shield forwardly; Figs. 1^a and 1^b are detail sections through air locks in the shield; Fig. 2 is a view substantially similar to Fig. 1, illustrating the shield as shoved forwardly in the earth, showing the faces of several working air chambers on different planes ready for excavation thereof; Fig. 3 is an enlarged detail section of the cutting edge of a chamber of the shield; Fig. 4 is an end view of the shield looking from the lefthand side of Figs. 1 and 2; Fig. 5 is a cross section of an air lock of the shield; Fig. 6 is a perspective view within a tunnel looking in the direction of my improved shield, illustrating a step in the erection of blocks in the tunnel lining; Fig. 7 is a vertical section of my improved shield provided with movable working air chambers; Fig. 8 is an enlarged detail of part of Fig. 7; Fig. 9 is an enlarged section illustrating movable working air chambers of the shield; Fig. 10 is an enlarged detail of part of Fig. 9.

In the accompanying drawings the numeral 1 indicates the skin or shell of the main body portion of my improved shield, which may be constructed in any approved manner, such as by means of plates, beams and the like properly riveted and bolted together as usual in a circular form of tun-

nel shield. Within the tail of the shield the rings 2 of the tunnel lining may be erected in any usual or suitable manner, which rings may comprise blocks 2^a of concrete, metal, or other material installed in any desired manner. Within the shield, and forward of the tail portion where the lining is erected, are working air chambers indicated at 3, 4, 5, 6, which are open at their forward or cutting edges, which forward or cutting edges are on different planes and said chambers are on different levels. There may be two or more such chambers on different levels according to the diameter of the shield or the work to be done. I have illustrated chambers on four levels assuming that the shield illustrated is adapted for the construction of a tunnel of relatively large diameter, say from forty to fifty feet in diameter. The floor or bottom wall 7 of the lowest chamber and the roof or upper wall 8 of the upper chamber may be comprised in the wall or skin of the shield, and the floors of the intermediate chambers may comprise platforms 9, 10 and 11 suitably built horizontally within the shield. Such floors or platforms may comprise horizontally disposed beams 12 and upper and lower plates 13, 14, preferably riveted together and secured to the skin of the shield, whereby the floors or platforms will be united to the skin of the shield in a rigid and air tight manner. A partition or wall is indicated at 15 at the rear of each chamber, and which may be secured to beams 16 that are secured between the several floors. Angle irons at 17 may be provided between the floors, walls 15 and beams 16 for rigidly securing them together and to make air tight joints. At 18 are air locks for each chamber adapted to open at one end within the corresponding chamber and at the other end within or toward the tail of the shield behind the wall 15. Said air locks may be of any approved form secured air tight in openings in the walls 15, as by means of angle irons 20 riveted respectively to the wall 15 and posts 16. Doors 21, 22 are provided at opposite ends of said air locks to permit the passage of men and materials to or through the air locks. Since there will be, under some conditions of use of my improved shield, material difference of air pressure in the several chambers with respect to that in the main tunnel with which the air locks communicate, I provide means for hinging said doors either on the exterior or the interior of the corresponding end walls of the air locks to close the respective end openings thereof, as circumstances may require. For such purpose the doors have hinge members 23 on one edge, co-operative with butts 24, 25 at the respective ends of the air locks. The butts 24 are shown on the exterior of the forward and rearward ends of the air locks, on the lefthand sides facing the locks from either end, (Figs. 1, 1^b, 2, 4 and 5), and the butts 25 are on the inside faces of the end walls of the air locks, but on the opposite sides of said end walls with respect to the exterior butts 24 thereof (Figs. 1^a and 2), whereby the doors 21 and 22 may be hung to close against the exterior or the interior end walls of the locks as may be required. For instance, if the air pressure in a chamber 3, 4, 5 or 6 is greater than that in the tunnel, the doors may be hung against the ends of the air locks, as illustrated in Figs. 1 and 2, wherein the door 22 within the chamber closes against the exterior of the end wall of the lock within such chamber, and the door 21 within such lock closes against the inner wall at the rear of the lock toward the tail of the shield, whereby passage through such lock under such different air pressures may be effected. If, however, the air pressure within one of such chambers is equal to or lower than the air pressure within the tunnel such doors will be reversed, that is to say, the door 22 would be removed and replaced within the lock and hung upon its forward butts 25 therein to swing against the wall of the lock within the chamber, and the door 21 would be removed and hung upon the butts 25 within the tail of the shield, to swing against the exterior face of the wall at the rear of such lock, within the tail of the shield, whereby passage through the lock may be effected. The arrangement described is such that only one door is provided for each end of each lock, and by reason of the ability to shift the door so as to swing against the outer or the inner face of an end wall of the lock, there is no danger of improperly setting the doors at the ends of the lock with respect to air pressures, which might occur were two doors provided at each end of the lock, such as one exterior thereof and one therein.

With the arrangements described, air pressures may be maintained within the chambers 3, 4, 5, 6 of any desired degree irrespective of the air pressure maintained within the tail of the shield beyond the locks and within the tunnel, to hold back water and ground at the faces 26 in the excavations in the earth. The forward working or cutting edges of the chambers 3, 4, 5, 6, indicated at 3^a, 4^a, 5^a, 6^a, are in different planes and different levels, which is effected by having such cutting edge of one chamber extending forwardly beyond the main circumferential portion of the shield farther than the cutting edge of another chamber. In the accompanying drawings I have illustrated the cutting edge of chamber 2 as extending farther forwardly than the cutting edge of the chambers thereabove, the cutting edge 4^a as extending farther forwardly than 130

the cutting edges, 5^a, 6^a, and the cutting edge 5^a as extending farther forwardly than the cutting edge 6^a. Such arrangement will hold good with respect to the number of such compressed air working chambers as the shield may be provided with, whereby the chambers and their respective cutting edges extend beyond one another in steps. By the arrangement described a higher air pressure may be maintained in a lower chamber than in a chamber or chambers thereabove, and so on with respect to each of the chambers upwardly. The aforesaid cutting edges may be constructed in any suitable manner, such as by means of sections securely fastened respectively to the skin and to the walls or platforms 9, 10, 11 of the shield, as illustrated in Figs. 1, 2 and 4. Since the shield is circular in form, the lower cutting edge 3^b of chamber 3 and the upper cutting edge 6^a of chamber 6 are attached to the skin of the shield, (the cutting edges 3^a, 4^a, 5^a being respectively attached to the floors or platforms 9, 10, 11, as above stated), and the cutting edges 4^b, 5^b at the sides of the chambers 4 and 5 respectively are attached to the corresponding portions of the skin of the shield (see Fig. 4).

Within each working chamber 3, 4, 5, 6 suitable supports 27 and abutments 28 are secured adapted respectively to support and oppose suitable jacks 29, whose plungers or rams 30 are adapted to coöperate with suitable breast-boarding or sheeting and rangers 31, 32, placed against the corresponding faces 26 of the several excavations to temporarily retain such sheeting in a well known manner. Said jacks may be hydraulic jacks controlled in the usual way, (Fig. 2). At 33 are jacks fitted within the tail of the shield to coöperate therewith and with the tunnel lining rings 2, for shoving the shield forwardly, in any well known manner. The jacks 33 may be hydraulic jacks operated in a usual manner for shoving tunnel shields.

While I have illustrated and described a shield constructed with the working chambers 3, 4, 5, 6 arranged on different levels, with such chambers projecting respectively farther outwardly from the bottom to the top, somewhat in the nature of a flight of steps, it will be understood that the principle of my invention may be carried out in conjunction with a shield in which the air chambers project farther outwardly from the top downwardly than from the bottom upwardly, that is to say, that the upper cutting edge of an upper chamber projects farther outwardly than the upper cutting edge of another chamber or chambers therebelow, and so on correspondingly downwardly, so that the cutting edge of a lower chamber will project less outwardly than the cutting

edge of a chamber or chambers thereabove, as like steps leading backwardly. Such form of shield might be used for tunneling where sand is at the top and clay at the bottom, and the diffusion of the air within the ground will be such as to overcome the mingling of air of a higher pressure from a chamber on a lower level with air of a lower pressure in a chamber on a higher level, since the faces 26 of the excavations on the different levels are in different planes and considerable earth intervenes between the cutting edge of one chamber and the cutting edge of another chamber.

While I have described a tunnel shield wherein the working air chambers 3, 4, 5, 6 are fixed in relation to the main body of the shield and work together as a unit, it will be understood that my improvements also contemplate a shield wherein the air chambers have independent movement with respect to the shield and to one another. Such a construction is illustrated in Figs. 7 to 10. In such construction each of said chambers may be made with all of its walls separate from the parts of the shield, the rear wall 15 of each such chamber being secured to top, bottom and side walls 15^a thereof, rigidly connected together in any suitable manner, such as by posts 16^a. The cutting edges 3^a, 4^a, 4^b, 5^a, 5^b and 6^a will be suitably secured to the forward edges of the walls 15^a of the chambers 3, 4, 5, 6 to move therewith, and the air locks 18 will be attached to the walls 15 in manner before described to move with the corresponding chambers. The bottom walls of said chambers rest upon the floors or platforms 7, 9, 10 and 11. The rear portions of the cutting edges 3^a, 4^a, 5^a, 6^a are shown provided with webs 3^a, 4^a, 5^a, 6^a, respectively overlying or opposing adjacent parts of the floors 9, 10, 11 and the skin 8 of the shield, the cutting edge 3^b having a web 3^a opposing the skin at the lower part of the shield (Fig. 7). The interior of each of said movable working chambers may be provided with uprights or abutments to coöperate with the jacks 29 in a manner before described. Jacks 35 (such as hydraulic jacks before referred to) may be secured to each movable chamber 3, 4, 5, 6 in position for coöperation of its plunger or ram 36 with an abutment 37, such as an I-beam, secured within the shield behind the corresponding movable chamber (Figs. 7, 8 and 9), whereby said chambers may be moved forward toward the face of the excavation as required. The jacks 35 of each chamber may be located in a jack circle indicated at 18^a which may comprise plates 18^b and posts 18^c secured between the corresponding air lock 18 and wall 15^a of a working chamber, to prevent passage of air around the locks between the tunnel and the chambers (Figs. 7 and 8). With the arrangement described,

the desired air pressure may be maintained in each of said movable working chambers as in manner before set forth, and when the excavations at the open ends of such chambers have been completed for each step and the sheeting applied and sustained by the jacks 29, the jacks 35 of the corresponding movable working chambers may be operated to force such chambers forward in proper order to the required extent in accordance with the excavation made in front thereof, each chamber thereupon sliding forwardly within the shield. When such movements of said chambers have been completed, the entire shield may be moved forwardly by the operation of the jacks 33, the jacks 29 and 35 then being relieved of pressure as required while the shield moves forwardly along the chambers 3, 4, 5, 6 to a required position, and the work of excavating in front of said chambers may again proceed, and so on. By means of the movable working air chambers within the shield it will be apparent that all of the advantages before described may be carried out, and also that one of the movable chambers may be moved forwardly more or less for any given shove of the main body of the shield in case rock or other obstruction may have been encountered in front of such chamber which slowed the work as compared to the work done in front of the other chamber or chambers at any given time.

By means of the arrangements described, a plurality of faces or working points of the tunnel excavation are provided independent of one another, on different planes, and the height of each working face is less than the vertical diameter of the shield. While, under some circumstances, the air pressure in all of the chambers may be the same, and if, desired, the same as within the tail of the shield and the tunnel, a great advantage of my improvement is that the air pressure in one working chamber of the shield may be less than the air pressure in one or more other of such chambers, such as according to the diameter of the shield and the depth in the earth at which the tunneling is carried on. In other words, compressed air may be used of suitable pressure for the level at which any of the chambers is located, and not as customary in shield driven tunnels at a common pressure for the whole shield and tunnel, and the air pressure in one chamber will be maintained separate from the air pressure in the other chamber or chambers, by reason of the fact that the face 26 of the excavation of a lower chamber projects farther into the ground than the face 26 of the excavation of any chamber or chambers thereabove, since the air under a higher pressure escapes from a lower chamber into the ground in front in a plane different from the plane of the face or faces 26 thereabove.

As such air rises unconfined from a given working chamber of the shield it continually expands to the same pressure as the ground water at the level it is at the moment passing, and since each air chamber 3, 4, 5, 6 ⁷⁰ may have its compressed air regulated to suit the water pressure in the ground at its front, it is apparent that such air will not enter an upper chamber or affect its air pressure, since the pressure of the air escaping from a lower chamber never exceeds the pressure in the ground water holding it. While different air pressures have heretofore been suggested for tunnel shields, it was, so far as I am aware, only in connection with a shield having one common working face for excavation in the earth, hence the air pressure can pass from a chamber on one level to a chamber on another level to affect or raise the air pressure in the latter without the outside or independent diffusion in the ground of the air from the chambers, which my invention provides for. The work of excavation, applying the sheeting or breast-boarding and sustaining them ⁸⁵ with the jacks 29 may be carried on in each working chamber of the shield under a given pressure, without regard to the air pressure in any other chamber, whereby, when the faces 26 at the different levels of the excavation have all been completed to the required position for each chamber, the entire shield may be shoved forward a suitable distance so that similar work for the faces at the several levels may continue preparatory to ¹⁰⁰ another shove of the shield, and so on successively. It will be noted that during the excavation of a face 26 of a lower chamber of the shield, the earth above the forward portion of such chamber, into which the face ¹⁰⁵ 26 of the excavation of the chamber next above is being made, is sustained intact by the forwardly projecting upper portion of the lower chamber, and so on for the chambers on each level, such earth above such forwardly projecting portion of a lower chamber thereby acting as an obstruction against the flow of compressed air from a chamber below into another chamber above.

Another important feature of my invention is that in cases where the top of the shield is situated only a short distance below the water level, or even above the water level, one or more working chambers may have the doors of their air locks arranged to hold ¹¹⁵ against a higher air pressure in the tunnel than in a working chamber, whereby a tunnel may be driven with water in front of the shield in its lower part held by compressed air in its lower working air chambers, with the tunnel itself containing compressed air which is prevented from escaping at the top by means of the upper air chamber or chambers either holding air of lower pressure than that in the tunnel, or even free ¹²⁰ ¹²⁵ ¹³⁰

air when such chamber is above the water level. A further important feature of my invention is that the use of compressed air may be restricted to the working chambers 5 of the shield, leaving free air in the tunnel.

An advantage of my invention is that since a lower air pressure may be maintained in an upper chamber than in a lower chamber, a great saving in the cost of operation 10 may be effected, because of the less cost of maintaining such air pressure and because wages of the workmen are less under low air pressure than under high air pressure, and they can work longer per day under low 15 air pressure than under high air pressure, and with less danger.

While I have illustrated the shield and lining rings of circular form, the latter constituting a circular cylinder, it will be 20 understood that a cylinder of any other form may be constructed by the method and apparatus set forth herein, the form of the cross section not being an essential part of my invention.

25 Having now described my invention what I claim is:

1. The method of constructing a shield driven tunnel consisting in excavating the ground at the front of a shield in separate 30 chambers on different levels and producing faces of the excavations in stepped relation in front of the several chambers, advancing the shield toward such faces, and erecting a lining within the tail of the shield after 35 such advances.

2. The method of constructing a shield driven tunnel consisting in excavating the earth in front of a shield in separate chambers on different levels and producing faces 40 of the excavations at the front of such chambers in different upward planes, maintaining air pressure greater in a lower than in an upper chamber to restrain the flow of water and material from said faces, advancing the shield toward said faces, and erecting a lining within the tail of the shield after 45 such advances.

3. The method of constructing a shield driven tunnel consisting in excavating the 50 earth in front of a shield in separate chambers on different levels in which a chamber on one level is longer in the direction of the tunnel than a chamber on another level, producing faces of the excavations in the front 55 of such chambers in different planes forward of one another, maintaining air pressure greater in a lower than in an upper chamber, advancing the shield bodily toward

said faces, and erecting lining within the tail of the shield after such advances. 60

4. A shield for tunneling having separate chambers at its forward end in a unitary structure, the forward end of one chamber extending farther outwardly than the forward end of another chamber. 65

5. A shield for tunneling having a plurality of working chambers in a unitary structure at its forward end on different levels, one chamber having a cutting edge located farther forward from the main body 70 of the shield than the cutting edge of another chamber.

6. A shield for tunneling having separate chambers in its forward part having their forward edges extending beyond another in 75 stepped relation, and an air lock for each chamber, said locks all being adapted to communicate with the space within the tail of the shield.

7. A shield for tunneling having a plurality of horizontal floors therein and transverse walls between the floors providing a plurality of chambers at the forward part 80 of the shield, one floor extending farther forwardly than another floor, and cutting edges at the forward ends of said floors located in different vertical planes.

8. A shield for tunneling having a plurality of horizontal floors therein, beams secured between said floors, transverse walls 90 secured to said beams and to the skin of the shield providing chambers on different levels within the shield, a chamber on one level extending forwardly from the main body of the shield farther than a chamber 95 on another level, and air locks in said walls.

9. A shield for tunneling having unitary chambers in its forward part extending beyond one another in horizontal stepped relation, jacks in tiers and upright supports therefor at the forward end of each chamber whereby the jacks in each chamber may hold sheeting at the face of the excavation in each chamber. 100

10. Apparatus for shield driven tunnels 105 comprising a shield having unitary air chambers in different levels and different face planes in stepped relation, and means for maintaining air pressure in one chamber independently of the pressure in any other 110 chamber.

Signed at New York city, in the county of New York and State of New York, this 29th day of January, A. D. 1918.

JOHN F. O'ROURKE.
